[57] CLAIM

The ornamental design for a cake slicer, as shown and described.

DESCRIPTION

FIG. 1 is a top, front and side perspective view of a cake slicer, showing my new design;

FIG. 2 is a top plan view thereof;

FIG. 3 is a bottom plan view thereof;

FIG. 4 is a rear elevational view thereof;

FIG. 5 is a front elevational view thereof;

FIG. 6 is a right side elevational view thereof; and,

FIG. 7 is a left side elevational view thereof.

The design is characterized by a pair of hemispherical pads provided at the transition areas between the opposed sides of the handle and the slicing head.
